UNITED STATES PATENT OFFICE

172,930

FIREPLACE

George Kosmak, San Francisco, Calif.

Application June 26, 1953, Serial No. 25,674

Term of patent 14 years

(Cl. D81—7)

To all whom it may concern:

Be it known that I, George Kosmak, a citizen of the United States of America, residing at 45 Castle Street in the city and county of San Francisco and State of California, have invented a new, original, and ornamental Design for a Fireplace, of which the following is a specification, reference being had to the accompanying drawing, forming part hereof.

I claim:

The ornamental design for a fireplace, as shown.
